UNITED STATES PATENT OFFICE.

ERNEST BOENING, OF YONKERS, NEW YORK, ASSIGNOR OF THREE-FOURTHS TO WILLIAM D. BALDWIN, OF SAME PLACE, AND JAMES H. WALLING, OF BROOKLYN, NEW YORK.

RATCHET MECHANISM.

SPECIFICATION forming part of Letters Patent No. 595,598, dated December 14, 1897.

Application filed March 3, 1897. Serial No. 625,840. (No model.)

To all whom it may concern:

Be it known that I, ERNEST BOENING, a citizen of the United States, residing at Yonkers, in the county of Westchester and State 5 of New York, have invented certain new and useful Improvements in Ratchet Mechanism; and I do hereby declare the following to be a full, clear, and exact description of the invention, such as will enable others skilled in the 10 art to which it appertains to make and use the same.

My invention is an improved contrivance of ratchet mechanism for drills, registering mechanism, and other apparatus, whereby the 15 ratchet-wheel is actuated both in the forward and backward movements of the operating-lever with economy of time and labor, as hereinafter described, reference being made to the accompanying drawings, in which—

20 Figure 1 is a sectional elevation of my improved ratchet mechanism contrived for working drills and other devices. Fig. 2 is a plan view of one side of the apparatus with the cover removed. Fig. 3 is a plan view of the 25 other side of the apparatus. Fig. 4 is a section showing a modification of the drill mechanism. Fig. 5 is a side elevation of the apparatus applied to a hoisting-drum.

20 A ratchet-wheel *c* is mounted revolvably on a base-plate *b* for turning a socket, as *a*, for the shank of a drill, or a shaft or other means of imparting motion to anything to be intermittently rotated, said ratchet-wheel being preferably placed with its side against that 35 side of the base-plate, and on the opposite side of the base-plate is a reduced extension *d* of the socket through a bearing-hole in the base-plate for the socket, on which extension the operating-lever *e* is mounted.

40 The short arm of the operating-lever is coupled by a link *f* in a toggle-joint, with a stud *g* projecting through a slot *h* of the base-plate, which is radial to the lever-pivot, said stud adapted to reciprocate in said slot 45 and said joint adapted to vibrate each way across the line of movement of the stud, and on the opposite side of the base-plate the stud *g* is connected to the shank of a hook-pawl *h'*, arranged in suitable relation to the ratchet- 50 wheel for actuating it when the stud is recip-

rocated in the slot. A suitable retaining-pawl *i* is provided to prevent reverse motion of the ratchet-wheel.

In Fig. 1 the usual extension-pivot *m*, employed in ratchet-drills for feeding the drill, 55 is applied to the pivot-stud *d*, on which the lever is mounted, said stud being suitably prolonged for the purpose.

For the purposes of a ratchet-drill a handle *s* will be attached to the base-plate *b*, by 60 which to hold it against the tendency of the lever thrusts to turn the base-plate when forcing the stud *g* outward.

In Fig. 4 the stud *d'* is made separately from the socket and is fixedly attached to the 65 base-plate, so as not to revolve, and the socket has a ball-bearing *u* under the base-plate for reducing the friction, which may be a preferable form of construction in some cases. A locking-pawl *j* is attached to or formed on the 70 shank of pawl *h'*, which takes effect on the ratchet-wheel when the operating-pawl *h'* is at rest for a more positive security against 75 wrongful movement of the ratchet-wheel without movement of the lever, especially forward, for false counting, which is a precaution that is desirable in some uses of the apparatus, as when the ratchet-wheel is utilized as part of a registering apparatus, as in 80 my pending application, Serial No. 585,544, filed March 31, 1896, to which reference is made for a better understanding of the same.

In connection with the locking-pawl *j* means will be employed to lock the lever *e*, so that it cannot be actuated without being unlocked— 85 as, for instance, a lock *p* of any kind attached to the lever, so that its bolt may be shot into a socket *q* in the rim of the case in either position of the lever at rest.

In Fig. 5 the part *a'*, corresponding to the 90 socket *a* of Fig. 1, is connected to a hoisting-drum for utilizing the apparatus for turning it, as for raising heavy weights by hand, and the extension-pivot *m* is omitted. The base-plate *b* is in this case secured against 95 the lever thrusts by connection with the drum-housing, as at *t*.

It will be seen that a forward-and-backward movement of the pawl *h'* is effected and a forward movement is imparted to the ratchet- 100

wheel by each single movement of the lever *e*, through the movement of pivot-joint *o*, from one side to the other of the radial line in which the pawl-carrying stud *g* slides, and 5 it will also be seen that the apparatus may be utilized for actuating various intermittently-rotating devices, as the pointer of a register.

I claim—

1. In a ratchet mechanism, the combination 10 of a base-plate, a ratchet-wheel mounted for rotation on said base-plate for transmitting motion, a lever pivoted in the axis of said ratchet-wheel, a pawl-carrying stud reciprocating radially to the said axis, a pawl attached to said stud and adapted to actuate the ratchet-wheel, and a link coupling said pawl-carrying stud to the short arm of the lever in a toggle-joint adapted to work each way across the line of movement of the pawl-carrying 15 stud substantially as described.

2. In a ratchet mechanism, the combination 20 of a base-plate, a socket or shaft pivoted on said base-plate for rotation on its axis, a ratchet-wheel attached to said socket or shaft for turning it, a lever pivoted in the axis of said socket or shaft, a pawl-carrying stud reciprocating radially to the said axis, a pawl attached to said stud and adapted to actuate the ratchet-wheel, and a link coupling said 25 pawl-carrying stud to the short arm of the lever in a toggle-joint adapted to work each way across the line of movement of the pawl-carrying stud substantially as described.

3. In a ratchet mechanism, the combination 30 of a base-plate, a socket or shaft pivoted on said base-plate for rotation on its axis, a ratchet-wheel attached to said socket or shaft for turning it, a lever pivoted in the axis of said socket or shaft, a pawl-carrying stud reciprocating radially to the said axis, a pawl attached to said stud and adapted to actuate 35 the ratchet-wheel, and a link coupling said pawl-carrying stud to the short arm of the lever in a toggle-joint adapted to work each way across the line of movement of the pawl-carrying stud substantially as described.

4. In a ratchet mechanism, the combination 40 of a base-plate, a socket pivoted on said base-plate for rotation on its axis, a ratchet-wheel attached to said socket for turning it, a lever pivoted in the axis of said socket, a pawl-carrying stud reciprocating radially to the said axis, a pawl attached to said stud and adapted to actuate the ratchet-wheel, a link coupling said pawl-carrying stud to the short arm of the lever in a toggle-joint adapted to work each way across the line of movement of the pawl-carrying stud, and a feed-screw, substantially as described.

5. In a ratchet mechanism, the combination 45 of a base-plate, a socket pivoted on said base-plate with a ball-bearing of its end against said base-plate, a ratchet-wheel attached to said socket for turning it, a lever pivoted in the axis of said socket, a pawl-carrying stud reciprocating radially to the said axis, a pawl attached to said stud and adapted to actuate the ratchet-wheel, a link coupling said pawl-carrying stud to the short arm of the lever in a toggle-joint adapted to work each way across the line of movement of the pawl-carrying 50 stud, and a feed-screw, substantially as described.

6. In a ratchet mechanism, the combination 55 of a base-plate, a socket pivoted on said base-plate for rotation on its axis, a ratchet-wheel attached to said socket for turning it, a lever pivoted in the axis of said socket, a pawl-carrying stud reciprocating radially to the said axis, a pawl attached to said stud and adapted to actuate the ratchet-wheel, a link coupling said pawl-carrying stud to the short arm of the lever in a toggle-joint adapted to work each way across the line of movement of the pawl-carrying 60 stud, and a feed-screw, substantially as described.

7. In a ratchet mechanism, the combination 65 of a base-plate, a socket pivoted on said base-plate with a ball-bearing of its end against said base-plate, a ratchet-wheel attached to said socket for turning it, a lever pivoted in the axis of said socket, a pawl-carrying stud reciprocating radially to the said axis, a pawl attached to said stud and adapted to actuate 70 the ratchet-wheel, a link coupling said pawl-carrying stud to the short arm of the lever in a toggle-joint adapted to work each way across the line of movement of the pawl-carrying stud and a feed-screw substantially as de- 75 scribed.

In testimony whereof I affix my signature in presence of two witnesses.

ERNEST BOENING.
